METHOD OF FORMING THE ANODES OF
ELECTROLYTIC CONDENSERS AND APPA-
RATUS FOR USE THEREIN

Julius Edgar Lilienfeld, Winchester, Mass.

Application March 20, 1931, Serial No. 524,004

19 Claims. (Cl. 175—315)

The invention relates to a novel procedure for the production of the anodes of electrolytic condensers, and to apparatus utilized in carrying out the same.

5 It has for an object to simplify this procedure in many of the various operations required on the anodes, particularly the polarization thereof, may be performed while said anodes are mounted on a suitable holding panel which is adapted to 10 receive a plurality of these anodes, thus facilitating the handling of the same in quantity and obviating damage thereto.

A further object of the invention resides in the method of procedure whereby not only is the 15 time of operation greatly reduced but a more perfect anode is obtainable because of greater safety in the handling, and wherein, also, leak losses are reduced to a minimum when the anode is placed in service. The invention has for a still 20 further object to obviate the use of all racks and like supporting means which are generally so utilized as to require troublesome cleaning after each formation operation.

A still further object of the invention resides 25 in the provision of means for affording a substantial contact, and individually with each anode unit, for the formation current.

Further features of the invention reside in the provision of means for retaining automatically 30 the electrolyte at a predetermined temperature; also, in the provision of suitable associated stirring means whereby the uniformity of the electrolyte is maintained throughout the period of forming the anodes which are arranged to dip 35 therein.

In carrying out the invention, the anodes to be treated are temporarily to be secured in position 40 on a suitable carrying panel therefor with the anode terminals available above the surface of the said carrying panel so that electrical contact may be made individually to the respective terminals above the surface of the electrolyte in which the anodes are to be formed. The said holding panel with anode units carried thereby 45 may then be handled together in the various operations to be performed on the said anodes. For example, the block of anodes may be subjected to an initial cleaning operation, then formed in a suitable electrolyte and again 50 cleaned and washed, whereupon the same are in proper condition for insertion into a suitable and final container, and are detached from the supporting panel to be secured in position in the condenser or like container provided. Provision 55 is made, furthermore, whereby the cover mem-

ber for the condenser container may be carried by the stem or terminal connection of an anode, being located somewhat below the outer end of the terminal and insulated from the anode, which latter and its stem portion are adapted to dip 5 into the electrolyte to be formed or provided with a polarizing film. It is understood, however, that the anode retaining member or panel is at no time submerged in the electrolyte, but is arranged to be located just above the level of the 10 same in the formation tank, and may comprise a suitably shaped sheet of aluminum.

The nature of the invention, however, will best be understood when described in connection with the accompanying drawings, in which:

Fig. 1 is a vertical section through the novel formation apparatus with electrodes positioned in the forming tank thereof, and taken on the line 1—1, Fig. 2.

Fig. 2 is a plan thereof with portions broken 20 away to disclose the underlying parts.

Fig. 3 is a fragmentary elevation and part section illustrating the mounting of a type of anode different from that shown in Figs. 1 and 2.

Referring to the drawings, 10 designates a suitable tank or container for an electrolyte 11 whose level is designed to be maintained slightly below a panel or cover member 12 for the tank, and is preferably of aluminum and arranged to rest temporarily upon a supporting rim 13 at the upper portion of the said tank. An overflow 14 insures against this level being exceeded, and provision is made, furthermore, for maintaining substantially constant the temperature of said electrolyte within the tank. For example, a heating 25 coil 15 and a cooling coil 16 may be disposed in the bottom of said tank, the former being designed to receive a heating medium such as steam and the latter cool water, the supplies of the respective media being controlled in any 30 well-known or special manner through automatic apparatus indicated at 17 and controlled by a thermally responsive member 18 inserted into the electrolyte. A stirrer mechanism 19 may also be introduced through the panel 12 of the 35 tank for effecting a substantially uniform temperature throughout the volume of liquid within said tank, and is carried by a contact plate 20 mounted above the panel 12, power for the stirrer mechanism being provided through the flexible 40 shaft 21.

The contact plate 20 as well as the stirrer mechanism is preferably suitably suspended, as through cables 22 attached to the said plate by the hooks 23, so that it may be readily lifted from 45

above the tank to allow of removal and insertion of the panel 12. Plate 20, moreover, carries a plurality of individual contact-making elements as the rods 25 which are spring-urged by means of springs 26 toward the panel 12 for contact-making purposes, as will hereinafter be more fully set forth.

The individual elements 25 are electrically interconnected through bus bars 27 to which electric power for effecting the polarization or formation operation is introduced at the terminal lug 28. Provision is made, also, for securing the plate 20 to the tank in vertically disposed relationship thereto as by means of shouldered bolts 29 and nuts 30, said bolts being adapted to fit slots 31 laterally cut inwardly from the edges of the plate to accommodate the bolts.

The panel 12 is provided with a plurality of perforations 35 spaced coaxially with respect to the rods 25 when plate 20 is located by means of the bolts 28 and slots 31 as hereinbefore described. These perforations are designed to mount properly for contact the outer ends of the anodes 36, which anodes are adapted to be supported and to depend therefrom in manner to dip into the electrolyte 11. For example, if the anode be of the type more particularly set forth in my copending application Serial No. 515,885, filed February 14, 1931, in which there is attached to the riser 37 of an anode, through an intermediate insulator member 38, a metal sleeve 39, this sleeve extends in part through an opening or perforation 35 and projects beyond the top of panel 12. It is, furthermore, provided with a threaded portion 40 designed to engage with a threaded metallic washer 41 fitted into a corresponding perforation. The flange 42 at the lower end of the sleeve is located below the panel and, in the particular embodiment, affords the cover element for a condenser container (not shown) and within which an anode after formation is eventually to be located, as more particularly set forth in my aforesaid copending application. A terminal, such as a wire 43, projects beyond the insulator 38, being bent over at its outer end as indicated, and is designed to receive the lower end or head of a corresponding contact-making element 25 which is resiliently urged thereto by its spring 26 to thus afford temporarily adequate contact with the anode.

Or, reference being had to Fig. 3 of the drawings, an anode 45 may be assembled to have its riser portion 46 arranged to extend through an insulation washer or gasket 47 which is adapted to be seated in an opening 35 of the panel 12. The riser in this instance is provided with a shoulder 48 designed for subsequent engagement with the sealing gasket associated with the condenser cover element (not shown) in the final mounting of the anode in a condenser. A locking nut 49 is also associated with the anode fitting over the threaded end of the riser, and is to be unscrewed to an extent sufficient to lower said shoulder 48 and adjacent riser portion for complete immersion in the electrolyte 13 during the formation operation. This is of particular importance for the reason that when said shoulder is thereafter tightened against a sealing gasket in the condenser assembly, the surface of the same has been completely formed so that there will be no tendency of corrosion in the subsequent operation of the condenser. When not thus formed, satisfactory operation of a condenser is not possible in that the upper portion 76 of an anode will eventually be eaten through and

the anode caused to drop off into its container, leak and power loss in the meantime, furthermore, constantly increasing.

In thus mounting a plurality of anodes upon a carrying panel such that said anodes may dip simultaneously into an electrolyte contained within the tank upon which said panel is supported, the formation operation may be conducted, through the particular manner of effecting contact with the outer end of a riser anode, to obviate the contact-making elements being affected in any way by the said electrolyte. Furthermore, the panel member provides a convenient rack or holding device for a multiplicity of the respective anodes to enable them to be handled conveniently and safely for the various preliminary operations thereon and operations subsequent to formation.

For example, the anodes thus assembled on the panel may be subjected en masse to a cleansing operation such as is more particularly set forth in my copending application, Serial No. 515,884, filed February 14, 1931. After the cleansing treatment they may be washed in water and then introduced into the formation tank, and after formation again washed and finally detached from the panel member for mounting in a suitable container to afford a condenser or rectifier.

It is to be observed that the particular arrangement set forth obviates entirely troublesome cleaning of a rack member and the like after each formation operation, and the entire procedure is accomplished in a much less time than heretofore and with greater facility. By providing individual contacting means for the respective anodes, a uniform power distribution is had, each anode receiving the proper current and voltage and whereby a more uniform production is attained.

Moreover, contact with an anode terminal may be made directly with a non-polarizable metal suitable for the purpose, such as copper, tin, etc. The end of a rod 25 or the rod as a whole is then constituted of this metal which, even in instances where the electrolyte should by accident come in contact therewith, could not become polarized and assume a disturbingly high resistance, whereby adequate contact is assured under all conditions. Furthermore, the entire apparatus is readily assembled and placed in operation, and the danger of damage to an anode during operation is reduced to a minimum.

While throughout the specification and claims the anode formed in accordance with the invention has been referred to as suitable for use in a condenser, it is to be understood, of course, that it is equally suitable for use in electrolytic rectifiers or other apparatus of an electrolytic nature.

I claim:

1. The method of forming anodes for electrolytic condensers, which comprises assembling externally of the forming tank an anode in its final holding fixture, loosening the anode to lower its riser portion relatively to the fixture somewhat below the normal position when in service, removably mounting the anode on the forming tank to dip into the electrolyte and immerse substantially the lowermost portion, applying electric current to the anode externally of the immersed portion, then removing the anode from the electrolyte, and finally tightening the anode to its holding fixture.

2. Apparatus for forming anodes for electrolytic condensers, comprising a tank for elec-

trolyte, a conductive panel removably supportable on the tank and adapted to temporarily mount a plurality of polarizable anodes to dip into the electrolyte, the said anodes each having a terminal element projecting above the panel, means to insulate the anodes individually from the panel, and means adapted to make electrical contact individually with the respective terminal elements for supplying electric current to the anodes.

5 3. Apparatus for forming anodes for electrolytic condensers, comprising a tank for electrolyte, a conductive panel removably supportable on the tank and adapted to temporarily mount a plurality of polarizable anodes to dip into the electrolyte, the said anodes each having a terminal element projecting above the panel, means to insulate the anodes individually from the panel, and non-polarizable means adapted to make electrical contact individually with the respective terminal elements for supplying electric current to the anodes.

10 4. Apparatus for forming anodes for electrolytic condensers, comprising a tank for electrolyte, an aluminum panel removably supportable on the tank and adapted to temporarily mount a plurality of polarizable anodes to dip into the electrolyte, the said anodes each having a terminal element projecting above the panel, means to insulate the anodes individually from the panel, and non-polarizable means adapted to make electrical contact individually with the respective terminal elements for supplying electric current to the anodes.

15 5. Apparatus for forming anodes for electrolytic condensers, comprising a tank for electrolyte, a conductive panel removably supportable on the tank and adapted to temporarily mount a plurality of polarizable anodes to dip into the electrolyte, the said anodes each having a terminal element projecting above the panel, means to insulate the anodes individually from the panel, and a plurality of means mounted above the panel for making contact individually with the respective terminal elements.

20 6. Apparatus for forming anodes for electrolytic condensers, comprising a tank for electrolyte, an aluminum panel removably supportable on the tank and adapted to temporarily mount a plurality of polarizable anodes to dip into the electrolyte, the said anodes each having a terminal element projecting above the panel, means to insulate the anodes individually from the panel, and a plurality of means mounted above the panel for making contact individually with the respective terminal elements.

25 7. Apparatus for forming anodes for electrolytic condensers, comprising a tank for electrolyte, a conductive panel removably supportable on the tank and adapted to temporarily mount a plurality of polarizable anodes to dip into the electrolyte, the said anodes each having a terminal element projecting above the panel, means to insulate the anodes individually from the panel, and means adapted to make electrical contact individually with the respective terminal elements.

30 8. Apparatus for forming anodes for electrolytic condensers, comprising a tank for electrolyte, a conductive panel removably supportable on the tank and adapted to temporarily mount a plurality of polarizable anodes to dip into the electrolyte, the said anodes each having a terminal element projecting above the panel, means to insulate the anodes individually from the panel, and means adapted to make electrical contact individually with the respective terminal elements.

35 9. Apparatus for forming anodes for electrolytic condensers, comprising a tank for electrolyte, temperature-regulating coils mounted within the tank for respective heating and cooling fluids adapted to maintain a predetermined

temperature of the electrolyte therein, thermally responsive means subjected to the electrolyte in the tank for controlling the supply of heating and cooling fluids to the regulating coils, a panel removably supportable on the tank and adapted to mount temporarily a plurality of polarizable anodes to dip into the electrolyte, the said anodes each having a terminal element projecting above the panel, and means adapted to make electrical contact individually with the respective terminal elements for supplying electric current to the anodes.

40 10. Apparatus for forming anodes for electrolytic condensers, comprising a tank for electrolyte, temperature-regulating coils mounted within the tank for respective heating and cooling fluids adapted to maintain a predetermined temperature of the electrolyte therein, thermally responsive means subjected to the electrolyte in the tank for controlling the supply of heating and cooling fluids to the regulating coils, stirrer means for the electrolyte, a panel removably supportable on the tank and adapted to mount temporarily a plurality of polarizable anodes to dip into the electrolyte, the said anodes each having a terminal element projecting above the panel, and means adapted to make electrical contact individually with the respective terminal elements for supplying electric current to the anodes.

45 11. Apparatus for forming anodes for electrolytic condensers, comprising a tank for electrolyte, a panel member having a plurality of threaded openings and removably supportable on the tank, polarizable anodes with respective threaded ends adapted to be screwed into the said panel openings to dip into the electrolyte and having corresponding terminals extending beyond the threaded portion, and contact-making means adapted for individual engagement with the respective terminals.

50 12. Apparatus for forming anodes for electrolytic condensers, comprising a tank for electrolyte, a panel member having a plurality of threaded openings and removably supportable on the tank, polarizable anodes having an end metal sleeve with exterior threads and bottom flange, said sleeve being adapted to be threaded into the corresponding panel openings and its attached anode adapted to dip into the electrolyte, an insulating bushing between an anode and its sleeve, and said anode having a terminal element extending beyond the bushing, and contact-making means adapted for individual engagement with the respective terminals.

55 13. Apparatus for forming anodes for electrolytic condensers, comprising a tank for electrolyte, a panel member having a plurality of threaded openings and removably supportable on the tank, polarizable anodes having an end metal sleeve with exterior threads and bottom flange, said sleeve being adapted to be threaded into the corresponding panel openings and the attached anode adapted to dip into the electrolyte, an insulating bushing between an anode and its sleeve, extending beyond the latter and containing a terminal from the anode extending beyond the outer end of said bushing, and a contact-making member mounted above the tank and panel and embodying a plurality of resiliently mounted contact-making elements adapted to register with the respective anode terminals.

60 14. Apparatus for forming anodes for electrolytic condensers, comprising a tank for electrolyte, a panel member having a plurality of threaded openings and removably supportable on the tank, polarizable anodes having an end metal sleeve with exterior threads and bottom flange, said sleeve being adapted to be threaded into the corresponding panel openings and the attached anode adapted to dip into the electrolyte, an insulating bushing between an anode and its sleeve, extending beyond the latter and containing a terminal from the anode extending beyond the outer end of said bushing, and a contact-making member mounted above the tank and panel and embodying a plurality of resiliently mounted contact-making elements adapted to register with the respective anode terminals.

65 15. Apparatus for forming anodes for electrolytic condensers, comprising a tank for electrolyte, a panel removably supportable on the tank

70 75 80 85 90 95

- and provided with a plurality of perforations, 5 tapped washers in the respective perforations, polarizable anodes with respective outer threaded ends adapted to be screwed into the said tapped washers, the said anodes having corresponding terminals extending beyond the threaded portion, and individual contact-making means adapted for engagement with the respective terminals.
14. The method of forming polarizable anodes, 10 which comprises insulating externally of the forming tank an anode in its final holding fixture, mounting a plurality of the anodes upon a common supporting panel above the surface of a suitable electrolyte to cause the anodes to dip 15 therein, and forming the anodes by introducing electric current simultaneously to all of the anodes by individually contacting the anodes above the panel.
15. The method of forming polarizable anodes, 20 which comprises insulating externally of the forming tank an anode in its final holding fixture, mounting a plurality of the anodes upon a common supporting panel above the surface of a suitable electrolyte to cause the anodes to dip 25 therein, and forming the anodes by introducing electric current simultaneously to all of the anodes by individually contacting the anodes externally of the electrolyte above the panel through a non-polarizable contacting element.
- 30 16. The method of forming anodes for electrolytic condensers, which comprises assembling externally of the forming tank an anode in its final holding fixture, loosening the anode to lower its riser portion relatively to the fixture some- 35 what below the normal position when in service, removably mounting the anode on the forming tank to dip into the electrolyte and immerse substantially the lowermost portion, applying electric current to the anode externally of the 40 immersed portion, then removing the anode from the electrolyte, and finally tightening the anode to its holding fixture and detaching it from the forming tank.
17. The method of forming the anodes for electrolytic condensers, which comprises insulating from one another and externally of the polarizing electrolyte a plurality of anodes by individually insulating an anode in its final holding fixture 5 and assembling a plurality of the fixtures upon a panel common thereto, introducing the anodes simultaneously into an electrolyte with cathode common to all of said anodes and while supported on the panel, and applying an electric current to 10 the outer ends of the anodes by simultaneously contacting the same above the panel and externally of the electrolyte.
18. The method of forming the anodes for electrolytic condensers, which comprises insulating 15 from one another and externally of the polarizing electrolyte a plurality of anodes by individually insulating an anode in its final holding fixture and assembling a plurality of the fixtures upon a panel common thereto, cleansing the anodes, 20 introducing the anodes simultaneously into an electrolyte with cathode common to all of said anodes and while supported on the panel, applying an electric current to the outer ends of the anodes by simultaneously contacting the same 25 above the panel and externally of the electrolyte, removing the panel, washing the anodes, and then detaching the said anodes from the panel and readjusting them in their respective holding fixtures. 30
19. The method of forming polarizable anodes, which comprises mounting externally of a suitable electrolyte a plurality of individual anodes to dip partly therein with cathode common to all of said anodes and with the respective free ends 35 of the latter exposed for contact, temporarily supporting said free ends externally of the electrolyte, and forming simultaneously all of said anodes by introducing electric current thereto by individually and simultaneously mechanically 40 contacting said free ends externally of the electrolyte.

JULIUS EDGAR LILJENFELD.
